METAL STUD

Edmund P. Burke, Los Angeles, Calif., assignor to
 Pacific Portland Cement Company, San Francisco, Calif., a corporation of California

Application June 2, 1937, Serial No. 146,032

5 Claims. (Cl. 72—115)

This invention relates to and has for an object the provision of a one-piece metal stud which may be fabricated in an inexpensive and efficacious manner from a single piece of plate or sheet metal without appreciable waste and in such manner that the chords and webs thereof are integral and of such relative arrangement and construction as to provide exceptional strength and stress resisting qualities in consideration of size, weight and material used, as well as to render the stud particularly well suited to metal lathing and many other uses in building constructions.

Another object of this invention is to provide metal studs of the character described wherein a most effective resistance to bending and other distorting stresses in a light and comparatively simple construction is provided for by a plurality of X-shaped webs formed integrally with the chords, the X-shape serving to reduce the unsupported length of and to materially strengthen said web members.

A further object is to provide a metal stud of the character described having chords of an angular cross section affording considerable strength and rigidity in consideration of lightness, size and material used.

Another object is to provide a novel and efficient joint structure for securing or splicing several of the studs of this invention in end-to-end relation without distorting the chords and webs and so that a strong joint may be quickly and easily made.

I have shown in the accompanying drawing a preferred form of metal stud apparatus embodying my invention, subject, however, to modification, within the scope of the appended claims, without departing from the spirit of my invention.

In the drawing:

Fig. 1 is a fragmentary front elevation showing a joint of studs of this invention and the particular construction of one form of stud under the provisions hereof,

Fig. 2 is an enlarged fragmentary section taken on the plane of line 2—2 of Fig. 1,

Fig. 3 is a cross section through one of the chords taken on the plane of line 3—3 of Fig. 1.

Fig. 4 is an enlarged section taken on the plane of line 4—4 of Fig. 1 showing the manner of joining the studs,

Fig. 5 is a fragmentary elevation similar to Fig. 1 showing a modified form of studs as when joined together in accordance with this invention,

Fig. 6 is an enlarged fragmentary cross section taken on the plane of line 6—6 of Fig. 5,

Fig. 7 is a cross section taken on the plane of line 7—7 of Fig. 5, and

Fig. 8 is an enlarged section taken on the plane of line 8—8 of Fig. 5 showing the manner of joining two studs.

60 One form of metal stud of this invention as

shown in Figs. 1 to 4 inclusive, is stamped from a single piece of sheet or plate metal and comprises like chords 9 and 10 and X-shaped web members 11 formed integral with said chords. Each chord is of angular cross section and consists of a flat base rail 12 with which the webs are integral, a flat side rail 13 somewhat narrower than the base rail and extending at substantially right angles thereto, and a flange 14 formed integral with the outer edge of the side rail and lying substantially parallel with and over the base rail, said flange being narrower than the side rail. Thus the chords may be said to be of channel form having their open sides opposed to one another and the flanges or sides (base rails 12) with which the webs are joined, considerably wider than the opposite flanges (flanges 14). This construction affords the strength of a full channel member of equal sides, with a saving in material and weight and affords an easier joining of two studs end to end as well as better provides for nesting and packing of the studs for shipment and storage, and furthermore greatly facilitates the tying of metal lathes and other structural elements to the stud.

Each X-shaped web consists in effect of four short, straight web sections 15 radiating from a common joint or center portion 16 located centrally of the space between the chords. The outer ends of these web sections 15 are formed integral with the base rails 12 of the chords. Each web section 15 is formed of arcuate cross section to define a rib 17 between its longitudinal edges along which latter narrow and flat edge portions 18 are formed and are substantially co-planar with the base rails 12 of the chords, whereas the convex sides of the ribs 17 are disposed in outwardly spaced relation to the plane of said rails 12. This construction affords considerable strength and offers effective resistance to strains and stresses. The reinforcing effect of the webs is enhanced by extending the ribs 17 angularly part way across the base rails 12 and this also strengthens the chords as well as prevents a hinge action at the juncture of the webs and chords.

Where a joint of two studs of this invention is made as shown in Figs. 1 and 4, a short spliced stud A corresponding in construction to the studs proper is interfitting with abutting end portions 50 of the studs to be spliced. The chords B of the spliced stud are somewhat smaller so as to nest as shown in Fig. 4, with the chords of the studs proper, whereas the webs C are X-shaped and closely overlie the webs 11. The resiliency of the metal makes possible the ready forcing of the spliced stud A into the splicing position shown in Figs. 1 and 4 and aids in holding the spliced stud in close fitting relation to the studs to be spliced.

On the chords **B** between the webs **C** are tongues **D** which are bent around edges of and lie against the base rails **12** of the two studs to be spliced as shown in Fig. 4, whereby to form a strong and rigid joint.

As shown in Figs. 5 to 8 inclusive a modified form of my invention comprises a stud made from a single piece of sheet metal to include chords **20** and **21** and X-shaped webs **22** joined to one another as in the first described form of the invention. In this form the chords are channel-shaped with the open sides facing one side of the studs, and the webs have flanges **23** whereby each straight web section **24** is of angular cross section as shown in Fig. 7. The flanges **23** are formed integral with minor chord flanges **25** that are located between the webs. Between the members **24** of each web are chord flanges **26** aligned with but spaced from the ends of flanges **25** distances substantially equal to the width of one of the web members **24**. This arrangement of flanges on the webs and chords provides considerable strength and resistance to damaging strains and stresses, whereby a strong, rigid stud may be inexpensively provided from a single piece of light gage sheet metal.

As shown in Figs. 5 and 8 a short spliced stud **E** is employed to join the ends of two of the studs proper. This spliced stud is identical with the studs proper except that it has no chord flanges corresponding to flanges **26** between the members of each web. It is nested in and overlies the end portions of the studs to be spliced and then secured in place by bending flanges **26** over the chords **F** and **G** as particularly shown in Figs. 1 and 8.

It should be noted that the ribs **17** shown in Figs. 1 to 4 inclusive and the flanges **23** and **25** shown in Figs. 5 to 8 inclusive constitute reinforcing elements of the chords as well as of the webs, in that in the one case the ribs **17** extend into the chords and in the other case the web flanges **23** are integral with the chord flanges **25** or vice versa.

It should also be noted that with reference to Figs. 5 to 8 inclusive, the flanges of the webs and chords are so arranged that a line drawn transversely across the stud at any point will intersect at least four equal flanges, whereby to provide maximum strength in a direction transversely of the stud.

It is important to note that the chords and webs hereof provide between them a plurality of large openings which are symmetrical on both sides of the longitudinal center line of the stud and have their centers equi-distantly spaced from one another on said line. By having the same spacing of said centers, regardless of sizes of the studs, the centers of said openings will align at the same predetermined equi-distantly spaced points throughout a wall, floor or like structure constructed of studs of the same or different sizes and therefore large uniform spaces are provided at readily determinable points for accommodation of pipes, conduits and other wall carried elements. Moreover, the X-shaped webs define substantially triangular openings smaller than the openings between the webs, but having the same spacing as the larger openings relative to one another and affording the same advantages, said triangular openings being primarily used for accommodation of bracing in wall and floor structures.

Another important feature of this invention is that the channeled chords provide for telescopically supporting and retaining connections and other structural elements, as shown in Fig. 4, without the use of extraneous fastenings or securing elements, or necessitating welding thereof.

I claim:

1. A one-piece metal stud comprising chords of channeled shape and wherein the open sides of said chords are opposed and the flanges defining one side of the channel are wider than the opposed flanges and X-shaped webs formed integral with the wider flanges of said chords, said webs being provided between their longitudinal edges with ribs of arcuate cross section and which are of greater length than said webs and extend partially across said wider flanges, said webs and chords defining between them openings having equi-distant centers on a common line extending longitudinally of said stud.

2. A spliced metal stud comprising two studs mounted end to end and each comprising channeled chords, crossed webs formed integral with one another and said chords, and a splicing stud overlapping the ends of said first-named studs and having channeled chords corresponding to but smaller than the first-named chords and adapted to nest therewith and tongues bendable to interlock the splicing and first-named studs, said stud units being provided with openings formed between the web members, which openings are symmetrical on opposite sides of the longitudinal center line of said units.

3. A one piece metal stud comprising parallel channel chords, each channel including a narrow flange and a wider flange, the open sides of said channels opposing each other with the wider flanges in substantially the same plane, X-shaped webs formed integral with said wider flanges and connecting the same, and ribs of arcuate shape embossed in said webs, said ribs being of greater length than said webs and extending into said wider flanges.

4. A one piece metal stud comprising parallel channel chords, each channel including a narrow flange and a wider flange, the open sides of said channels opposing each other with the wider flanges in substantially the same plane, X-shaped webs formed integral with said wider flanges and connecting the same, and ribs of arcuate shape embossed in said webs, said ribs being of greater length than said webs and extending into said wider flanges, said embossed ribs extending inwardly only from the plane of said wider flanges and webs.

5. A one piece metal stud comprising parallel channel chords, each channel including a narrow flange and a wider flange, the open sides of said channels opposing each other with the wider flanges in substantially the same plane, X-shaped webs formed integral with said wider flanges and connecting the same, and ribs of arcuate shape embossed in said webs, said ribs being of greater length than said webs and extending into said wider flanges, said X-shaped webs defining opposing triangular openings, said webs being spaced from each other longitudinally of the stud so that said triangular openings are longitudinally spaced a distance equal to the distance separating the centers of the spaces between webs.

EDMUND P. BURKE.
